(No Model.)

W. G. PRICE.

FARE BOX.

No. 326,778.

Patented Sept. 22, 1885.

UNITED STATES PATENT OFFICE.

WILLIAM GUNN PRICE, OF NEW ORLEANS, LOUISIANA.

FARE-BOX.

SPECIFICATION forming part of Letters Patent No. 326,778, dated September 22, 1885.

Application filed May 13, 1885. (No model.)

To all whom it may concern:

Be it known that I, WILLIAM GUNN PRICE, a citizen of the United States, residing at New Orleans, parish of Orleans, State of Louisiana, 5 have invented new and useful Improvements in Fare-Boxes, of which the following is a full and exact description, reference being had to the accompanying drawings, making part of this specification.

10 This invention relates to a fare-box having a pivotally-suspended push-block above the receiving-aperture thereof, a temporary receiver located beneath same, an alarm connected therewith in such manner as to be 15 sounded only at such times as fares are actually deposited therein, and a second temporary receiver for the separate exhibition of each deposit before the same is dropped to a lower platform and drawer, as in ordinary fare-boxes.

20 My invention will be more readily understood by referring to the accompanying drawings, whereon Figure 1 represents a front view of the fare-box with certain portions in section or omitted, in order that the mechanism may be more fully shown. Fig. 2 is a vertical section through the line $x x'$ of Fig. 1.

25 On the drawings, the letter A designates the casing, the inside of which is provided with side plates $b b'$, and with a drawer, B, and a dumping - platform, C, having an outwardly-projecting rod, d , to provide for its being tilted, and thus relieved of its contents as often as required. In the upper part of the 30 box is pivotally suspended a push - block, D, the under surface of which is provided with a toothed plate or comb, E, and an intermediate recess, e , for adapting the same to operate over that portion of the box which contains 35 the receiving - aperture. The teeth of the aforesaid toothed plate or comb are adapted to operate between those of a second toothed plate or comb, F, which is mounted on a shaft, G, pivoted or journaled in the side plates $b b'$, and held in position to receive the fares as 40 they are dropped through the aperture by reason of a counter-balance or rear projection, h , and a rod or stop, i , against which the latter rests when in its normal position. The 45 toothed plate or comb F is provided at each 50

end thereof with side plates ff' , to prevent the fares from dropping off the same, and to the rear end or counter-balance thereof is secured the stem f'' of a striker, f''' , whereby an alarm is sounded on a gong, H, as the push-block in 55 returning to its normal position causes its comb attachment to impinge against the fares, and thus tilt the lower comb until it has raked the said fares from off the same. The gong 60 H is riveted to the side pin, k , of a plate, l , (shown in dotted lines,) which is fitted in a recess formed between the plate b and the adjacent side of the casing, and which is provided with a lug, l' , tapped to receive the 65 screw-threaded end of an outwardly-projecting rod, m , whereby it is adjusted to the sound required.

To the stem f'' of the striker f''' is pivoted the upper end of a rod, N, the lower end of which is connected with a pin, n , formed on 70 the rear projection of a pivoted plate or temporary receiver, O, on which the fare is exhibited until the push-block is again thrust back and a second fare deposited in the box, when by reason of the aforesaid connections 75 the said receiver O opens downwardly and drops its contents to the lower platform, returning to its normal position in time to catch the next fare as it is tossed from the comb-receiver, and conveyed thereto by the glass 80 slide P, which is supported by the side plates $b b'$, as shown, and which permits of the fare being seen from the rear of the box as well as from the front of same, both the front and rear of the box being provided with glass 85 for said purpose. From the lower platform, C, the fares are dumped into the drawer beneath by means of the rod d , as in other fare-boxes now in use.

To deaden the sound which might arise 90 from the working of the push-block, rubber or other suitable bumpers are secured in rear of the box and recess e , as shown at R S. The front edges of the teeth of the upper comb are notched, as shown in the drawings, to prevent 95 the fares sliding up the same, and thus insure a better working of the apparatus. This feature is an improvement on United States Letters Patent No. 319,313, which were granted to me June 2, 1885.

Having described my invention, what I claim as new, and desire to secure by Letters Patent, is—

1. In a fare-box, the combination of a pivotedly-suspended push-block having a comb provided with notched teeth connected with the under side thereof, and a recess between said parts, whereby it is adapted to operate over the receiving-aperture of the box, as described, with a counterbalanced pivoted toothed plate or comb, and a rod or stop for limiting the movement of the latter, and thereby adapt same to receive and hold the fares until tilted and relieved of said fares by the dropping of the push-block and comb attachment to their normal positions, substantially as and for the purpose set forth.

2. In a fare-box, the combination, with a pivotally-suspended push-block having a toothed plate or comb connected with its under surface, as described, of a pivoted comb provided with side or end plates, the teeth of the combs adapted to operate between each other, substantially as and for the purpose specified.

3. In a fare-box, the combination of a pivoted counterbalanced toothed plate or comb adapted to be tilted by the forward movement of a pivotedly-suspended push-block, and a comb attachment having notched teeth adapted to operate between the teeth of the pivoted comb, as described, with a rod or stop for

limiting the movement of the latter, and a striker and gong for sounding an alarm as the fares are discharged from the comb-receiver, substantially as set forth.

4. In a fare-box, the combination, with a pivoted comb adapted to be held in position to receive the fares, as described, and a pivotedly-suspended push-block provided with a comb attachment, the teeth of which are adapted to operate between those of the former comb and to discharge the fares therefrom, as set forth, with a pivoted platform or trap, a rod connecting same with the tilting comb, whereby it is operated, and a glass slide for conducting the fares to the said platform for inspection before being dumped and mixed with other fares, substantially as specified.

5. In a fare-box, the combination, with a temporary receiver having a striker connected therewith, of a gong secured to a sliding plate provided with a screw-threaded socket and an adjusting-screw, whereby its relative position to the striker may be altered to increase or diminish the volume of sound, substantially as described.

In testimony whereof I affix my signature in presence of two witnesses.

WILLIAM GUNN PRICE.
